STANLEY D. LIVINGSTON, OF FREEPORT, NEW YORK, ASSIGNOR TO EISEMANN MAGNETO CORPORATION, OF BROOKLYN, NEW YORK, A CORPORATION OF NEW YORK.

TRANSFORMER FOR RADIOCIRCUITS.

Original application filed September 12, 1923, Serial No. 662,177. Divided and this application filed July 8, 1925. Serial No. 42,124.

My invention is for an improved construction of radio-frequency transformer embodying various features of novelty of prior devices, as will appear from a detailed description of the accompanying drawings which form part of this specification. In these drawings,

Fig. 1 represents a side view of a transformer constructed in accordance with my invention, one half of the device being shown in longitudinal cross-sections;

Fig. 2 shows the transformer mounted in a socket having terminals properly connected in circuit;

Fig. 3 is an end view of the transformer;

Fig. 4 is a bottom view showing the contacts projecting from the plug of the transformer;

Fig. 5 is an inside view of one of the half shells which constitute the outer casing of the transformer; and

Fig. 6 is an enlarged fragmentary view in cross-sections to show how the concave transformer contacts are in locking engagement with the rounded contact heads of the transformer socket.

The parts of the transformer are mounted in an outer shell or casing indicated as a whole by C. This casing is preferably molded out of composition material suitable for that purpose, such as bakelite or the like. In the preferred form of my invention, the outer shell C comprises two identical half sections 1 and 2. Each shell section is formed with a cylindrical recess 3 and a semi-cylindrical projection 4. Each projection 4 is formed with a recess 5 and a passageway 6 leading into the recess or chamber 3. When the two halves or sections 1 and 2 are assembled, they constitute a closed outer shell. The semi-cylindrical projections 4 fit together to form a cylindrical plug, which I will designate as a whole by G. The plug G is constructed to fit into a socket F mounted on a base plate B, which may form part of a radio-frequency amplifier unit. The socket F comprises an outer shell 7 and four insulated spring contacts 8, three of which are shown in Fig. 2. The arrangement of these contacts is similar to that of the well-known vacuum tube socket contacts, and will therefore be understood without further description. The transformer socket is very sim-

ilar to the standard lamp socket, except that the shell 7 is considerably lower than the usual vacuum tube socket shell. This difference in the heights of the two shells, makes it impossible to insert a vacuum tube by mistake into socket F, or to insert the transformer into a vacuum tube socket. A pair of pins 9, projecting laterally from the plug G at diametrically opposite points, are adapted to engage correspondingly arranged bayonet slots 10 in the shell 7 of the transformer socket F to insure correct positioning of the plug in the socket. Only one of the slots 10 is shown in Fig. 2, but the location of the other slot will be clearly understood. The shell sections 1 and 2 are provided with holes 11 through which pass bolts 12 for rigidly securing the two halves together. It will be seen from Figs. 1 and 4 that when the two shell sections are bolted together, they are in contact along a plane indicated by the line T, this plane being substantially at right angles to the longitudinal axis L of the cylindrical chamber or compartment formed by the recesses 3 of the two shell sections.

Within the cylindrical chamber 3 of the shell C are mounted the two transformer windings K and K'. Either winding may be the primary, depending upon the position of the plug G in socket F, as will presently be explained. These windings are in the form of cylindrical coils, which fit snugly in the chamber 3, as best shown in Fig. 1. In the chamber 3 is supported a magnetic core M of suitable construction. Personally, I prefer a core consisting of alternate layers of paper and thin sheets of magnetic material. The core M is hollow and the ends thereof engage projections 13 extending inwardly from the ends of the shell sections 1 and 2. In this way the magnetic core M is supported centrally with respect to the windings K and K' and is spaced therefrom by an air gap 14.

This arrangement of core and windings has certain practical advantages. The windings K and K' are separated sufficiently to reduce the distributed capacity to the lowest practical value. While this separation of the windings also reduces their mutual inductance, the magnetic core M increases the inductance to the required value. Now, the introduction of an ordinary magnetic core

in a radio-frequency transformer would again raise the distributed capacity above a permissible value. However, I obviate this objection by so mounting the magnetic core that nothing but air is between the core and the windings. This reduces the capacity effect between the core and windings to a minimum. Such a condenser effect as may be present introduces merely negligible losses because of the air dielectric. It will be clear that while the core M is preferable in certain instances, it is not always essential. For instance, in tuned radio frequency, where one winding is tuned with a condenser, the magnetic core may be omitted.

In the plug G of the transformer are embedded four contacts 15, 16, 17 and 18. Contacts 15 and 16 are embedded in one plug section, and contacts 17 and 19 in the other plug section. These contacts project into the shallow recess 5 formed in each shell section, as may be seen from Fig. 5, so that the ends of each winding may be connected to the pair of contacts carried by the same shell half or section. For instance, the ends of winding K are connected to contacts 15 and 16, and the ends of winding K' are connected to contacts 17 and 18. The ends of the windings are led to their respective contacts through the passage 6. By virtue of this construction, each half of the outer casing contains one winding connected to a pair of outer terminals. Each half is thus complete with its winding, contacts and connections, so that no cross-connections are necessary when the two halves are fastened together. This makes it easy to insert the coils in place and connect them with their respective contacts or terminals in the plug.

When the transformer is inserted in the socket F, the four plug contacts engage the socket contacts 8, which are supposed to be properly connected in circuit. These connections are well understood and need not be shown. The windings K and K' may have a one-to-one ratio, in which case it is immaterial which winding is the primary and which the secondary when the transformer is inserted in the socket. In certain cases, however, I prefer to make the windings of an unequal number of turns. For example, the ratio of turns in windings K and K' may be about 2:1, the long winding K being the primary and the short winding K' the secondary. If the plug G is so inserted in socket F that the position of the windings K and K' is the reverse of that indicated in Fig. 2, the short winding K' becomes the primary, and the long winding K is then the secondary. To cite an instance by way of illustration, I found in practice that with a 2:1 ratio in the windings, the tuning range for short waves came well within 150-400 meters, and for longer waves between 275-750 meters. Other ratios will give dif-

ferent tuning ranges. It will be understood, of course, that in either position of the transformer in socket F, the secondary winding is tuned by a condenser.

In order to inform the operator which position of the transformer in socket F produces a step-up or step-down relation of the windings, a suitable mark or indicator is provided. In Fig. 2, the outer shell C has a mark x so arranged that, when this mark is toward the front of the base, the short coil K' functions as secondary; when the transformer plug is so inserted that the mark is in the position indicated by the dotted lines x', the long coil K is connected in circuit as the secondary and is tuned by the condenser. It will be understood that any other practical indicating means may be employed.

In order to prevent accidental rotation of the transformer plug after being inserted in socket F, I provide means for releasably locking the plug contacts to the socket contacts. In the present instance, this releasable locking means consists in forming each socket contact 8 with a rounded head 19, as indicated in the enlarged view of Fig. 6. Each plug contact terminates in a hollow or concave projection 20, which snaps over the rounded head 19 when the plug is in proper position in the socket. It will be understood that the contacts of the transformer socket F, like those of a lamp socket, are resiliently supported. Therefore, the rounded heads 19 of the socket contacts snap into the hollow ends 20 of the transformer plug contacts, when the transformer is in proper position in the socket, as predetermined by the pins 9 engaging in the bayonet slots 10 of shell 7. The horizontal portions of the bayonet slots 10 lock the transformer plug against axial movement out of the socket. The locking engagement between the rounded heads 19 of the socket contacts and the hollow ends 20 of the transformer plug terminals, as above described, while locking these parts together against accidental separation, permits rotation of the transformer plug for removal from the socket.

Although I have herein shown and described a specific form of radio-frequency transformer, I want to make it clear that I have done so merely for the sake of explaining my invention which may be mechanically embodied in other forms than herein set forth, without departing from the scope of my invention as defined in the appended claims.

This application is filed as a division of my copending case Serial Number 662,177, filed September 12, 1923, in which an official requirement was made for the cancellation of all claims on the transformer construction herein set forth.

What I claim as my invention is:

1. A radio transformer comprising an outer shell consisting of two complementary sections adapted when assembled to form a chamber and a plug, a primary winding in the chamber of one section and a secondary winding in the chamber of the other section, a pair of contacts carried by each plug section and connected to the ends of the associated winding, and means for separably securing said sections together.
2. A radio transformer comprising an outer shell consisting of a substantially cylindrical hollow part and a plug projecting from said hollow part substantially at right angles to the axis of said part, said shell being divided into two similar halves along a plane passing transversely through said hollow part and said plug, a winding in the hollow portion of each half shell, a pair of contacts mounted in and projecting from the plug section of each half shell, the ends of each winding being connected to the associated contacts, and means for securing the half shells together.
3. A radio transformer comprising an outer shell consisting of a substantially cylindrical hollow part and a plug projecting from said hollow part substantially at right angles to the axis of said part, said shell being divided into two similar halves along a plane passing transversely through said hollow part and said plug, a winding in the hollow portion of each half shell, a pair of contacts mounted in and projecting from the plug section of each half shell, the ends of each winding being connected to the associated contacts, a magnetic core passing axially through said windings and spaced therefrom, the ends of said core engaging the opposite ends of said hollow part, whereby said core is supported lengthwise in said hollow part independently of said windings, and means for securing the half shells together.
4. A radio transformer comprising an outer shell consisting of a substantially cylindrical hollow part and a plug projecting from said hollow part substantially at right angles to the axis of said part, said shell being divided into two similar halves along a plane passing transversely through said hollow part and said plug, a winding in the hollow portion of each half shell, a pair of contacts mounted in and projecting from the plug section of each half shell, the ends of each winding being connected to the associated contacts, a hollow magnetic core passing axially through said windings and spaced therefrom, inside projections at the opposite ends of said hollow part for removably engaging the ends of said core, whereby said core is supported lengthwise in said hollow part and removable therefrom without disturbing said windings, and means for securing the half shells together.
5. In a radio transformer, a cylindrical shell consisting of two halves separable along a transverse plane, a winding in each half shell, and a magnetic core supported axially in said shell independently of said windings, said core passing through said windings and being spaced therefrom.
6. In a radio transformer, a cylindrical shell consisting of two halves separable along a transverse plane, inside projections at the opposite ends of said shell, a winding in each half shell, and a magnetic core extending axially through said windings and being spaced therefrom, the ends of said core being in supporting engagement with said projections.
7. As a new article of manufacture for use in radio transformers, an outer shell consisting of two substantially identical half sections adapted to fit together to form a closed cylindrical chamber and a plug, each plug half being provided with a recess communicating with the chamber of the section, and contacts embedded in each plug half and extending from said recess to the outside of the plug, for the purposes specified.
8. As a new article of manufacture for use in radio transformers, an outer shell of molded material consisting of two substantially identical half sections, each section comprising a hollow cylindrical portion with a semi-cylindrical portion projecting therefrom at right angles to the axis of said hollow portion, said sections being adapted to fit together to form a closed cylindrical chamber and a cylindrical plug extending transversely therefrom, for the purposes specified.
9. In a radio transformer, an outer shell of substantially T-shape form, one part of said shell containing the windings, and the other part constituting a plug adapted to fit in a socket, said plug having contacts connected to the windings.
10. A radio-frequency transformer having a pair of spaced windings arranged in axial alignment, a cylindrical magnetic core passing axially through said windings and uniformly spaced from each winding by an annular airgap, and means engaging only the ends of said core for supporting the same in position.
11. A radio-frequency transformer having a pair of spaced windings, a magnetic core passing axially through said windings and spaced from each winding by an airgap, said core being cylindrical and comprising thin sheets of magnetic material separated by insulating sheets, and means for supporting said core in that position.
